UNITED STATES PATENT OFFICE.

BENJAMIN F. A. SAYLOR, OF ROME, GEORGIA, ASSIGNOR, BY MESNE ASSIGNMENTS, TO STANDARD TURPENTINE & WOOD PULP COMPANY, OF ATLANTA, GEORGIA, A CORPORATION OF ARIZONA.

PROCESS FOR EXTRACTING TURPENTINE AND ROSIN FROM WOOD.

1,081,276.

Specification of Letters Patent.

Patented Dec. 9, 1913.

Application filed August 5, 1909, Serial No. 511,410. Renewed October 21, 1913. Serial No. 796,517.

To all whom it may concern:

Be it known that I, BENJAMIN F. A. SAYLOR, a citizen of the United States, residing at Rome, in the county of Floyd and State 5 of Georgia, have invented certain new and useful Improvements in Processes for Extracting Turpentine and Rosin from Wood; and I do hereby declare the following to be a full, clear, and exact description of the invention, such as will enable others skilled in the art to which it appertains to make and use the same.

My invention relates to improvements in processes for extracting turpentine and rosin 15 from resinous woods containing the same; and is an improvement upon my prior Patent No. 945,612, dated January 4, 1910.

The primary object of my invention is a 20 process whereby turpentine and rosin may be extracted from wood in a more economic and expeditious manner than previously, and whereby resins and turpentine can be produced in a better and purer state than formerly and at a less expense, leaving the 25 wood in a condition to be made into wood pulp.

In carrying out my invention I use an apparatus substantially the same as that described in my patent, above referred to.

30 In carrying out my invention I use a strong steel cylinder with a capacity of three or more cords of wood. This cylinder is provided with an opening 14 inches in diameter near the top thereof and arranged 35 in such a manner that the cylinder is steam-tight and air-tight when closed. At the bottom of the cylinder there is a valve and a short discharge pipe about 2 inches in diameter, ordinarily closed by a manhole

40 stances are withdrawn after they are extracted from the wood as hereinafter described. In the lower portion of the cylinder is a large opening about 14 inches in diameter, ordinarily closed by a manhole 45 valve, through which the wood and chips contained in the cylinder are discharged at the close of the process. The entire cylinder is provided with a steam jacket made sufficiently strong to withstand a considerable 50 pressure. A two inch steam pipe connects with this jacket, which is also provided with

a steam pressure gage, an automatic blow off valve, and an escape valve for removing the water of condensation. The cylinder is placed in an upright or slightly inclined position, and is provided with connections which lead to a vacuum pump and with an apparatus for purifying and distilling the substances contained by my process.

In the accompanying drawing which illustrates an apparatus for carrying out my invention, the figure represents said apparatus in cross section, partly in elevation, the supports being omitted.

a is the steel cylinder provided with an 65 opening *b* in its top, through which the material to be treated is fed into the cylinder, which opening is usually closed by the cover *c*, removably fastened thereto.

d represents the discharge pipe for the 70 resinous material at the bottom of the cylinder. The cylinder is provided with a man-hole opening *e*, through which the material after treatment is drawn out, and said man-hole is ordinarily closed by a cover *f*.

g represents the steam jacket, *h* the valved steam pipe leading thereinto, *i* the steam pipe leading into the bottom of the cylinder, *j* the pressure gage, *k* the escape valve, and *m* the valved discharge pipe for the 80 water of condensation.

n is the pipe for introducing steam and hot water to the cylinder at the top thereof, *o* a pipe leading into a closed vessel or condenser *p* which is connected by a pipe *q* 85 with the vacuum pump *r*. The vessel *p* is for the purpose of collecting any vapors that may be sucked out of the cylinder *a* by the pump, and this vessel is provided with a valved discharge pipe *s*.

t is an ordinary still provided with a steam coil *u* and having connected to its top an ordinary worm *v*, which runs through a condensing drum *w* and discharges into a receptacle *x*; *y* is a valved pipe connecting 95 the still *t* with the pipe *d*.

In carrying out my process I charge the cylinder with chips, slivers or blocks of pine or other resin-containing woods. Small quantities of steam or hot water, at a temperature not above 212° F., are then 100 introduced into the jacket of the cylinder

and the vacuum pump is started. This vacuum pump is kept in operation long enough to exhaust the air and to produce a vacuum amounting to about 26 inches of mercury, which usually requires about 5 twenty minutes. Steam is then admitted into the bottom of the cylinder through the pipe 1 passing through the jacket thereof, until a pressure of about 25 lbs. is obtained 10 within the cylinder, the pressure gage *j* being employed to indicate the pressure, the cylinder having been previously disconnected from the vacuum pump by the valves 2 and 3, and tightly closed. The valve 3 of the 15 pipe *o* leading to the vessel *p* is then opened and the steam which is in the cylinder is allowed to rush over and the turpentine that may be distilled off by the heat of the steam is condensed in the vessel *p* in order to save 20 the small amount which may come over.

The steam in passing out of the cylinder carries with it the air and when the pressure has run down to about 20 lbs. or less, all the air has been completely removed 25 from the cylinder. The cylinder is then closed and steam admitted as quickly as possible into the jacket through the pipe *h* and into the cylinder through the pipe 1, until a pressure of about 100 lbs. or more per square 30 inch is obtained in the cylinder. Under this heat and pressure and the absence of air in the cylinder, the resinous substances speedily distil or dissolve from the chips of wood, the rosin going to the bottom of the cylinder 35 or still and the turpentine and gases through the pipe *o* into the vessel *p*, where the turpentine is recovered. I keep up the pressure until nearly all of the turpentine has been extracted from the chips and passed over 40 through the condenser; then I stop the introduction of steam into the cylinder and jacket by closing valves 4 and 5 and gradually allow the pressure to subside. After the pressure has nearly subsided, however, 45 I open the valve 6 of the rosin outlet in the bottom and as a consequence the steam within the digester or cylinder rushes to this point and carries with it the rosin from within the cylinder, including that clinging 50 to the outside of the chips to the rosin outlet, thus cleaning the chips thoroughly. I find in practice, however, that before this outlet is opened, nearly all of the rosin has been extracted and has collected at the bottom of the cylinder. There being no air 55 present during the operation, except at the very first when the pressure and heat are low, and consequently no oxidizing agent, the turpentine is pure and sweet and without 60 bad odor and by redistillation becomes as clear as water.

After the rosin has all been drawn off from the bottom of the cylinder, I then force steam into the top of the cylinder

through the pipe *n*, still leaving the rosin 65 outlet open. As a result the steam rushes down through the chips, thoroughly cleaning them and leaving the wood in a condition suitable for making wood pulp. I have also found by actual trial that I can facilitate the extraction of the turpentine and resin from the wood by putting in during the preliminary part of the process about 70 10 lbs. of caustic soda in its dry state, per cord of wood, or when the cylinder is charged, as it is dissolved during the operation and penetrates and aids in cleaning the fiber of the wood. I can use a pressure as high as 200 lbs. if necessary and still preserve the fiber. 75

80 What I claim is:—

1. The process of treating resinous wood to recover the products thereof which consists in collecting fine particles of such wood in a closed cylinder, heating said cylinder 85 by externally applied heat and simultaneously therewith creating a vacuum in the cylinder; admitting steam under pressure into the cylinder at the bottom thereof and then allowing said steam to escape and carry off a portion of the turpentine and substantially 90 all of the air, and closing said cylinder when the pressure therein is reduced; again heating the cylinder by externally applied heat and admitting the steam into the cylinder until the required pressure is obtained to separate the rosin and turpentine from the wood in the absence of air; allowing said steam to escape during the maintenance of 95 said last-named pressure by the continued 100 injection of steam and carrying off the separated turpentine; stopping the introduction of the steam and allowing the pressure in the cylinder to subside; and finally 105 opening the bottom of the cylinder and allowing the residual steam therein to carry off the turpentine product, substantially as described. 110

2. The process of treating resinous wood to recover the products thereof which consists in collecting fine particles of such wood in a closed cylinder, heating said cylinder to about 212° F. by externally applied heat and simultaneously therewith creating a 115 vacuum in the cylinder amounting to about 26 inches of mercury; injecting dry caustic soda into the cylinder; admitting steam under pressure into the cylinder and then allowing said steam to escape and carry off a portion of the turpentine and substantially 120 all of the air, and closing said cylinder when the pressure therein has been reduced to about 20 pounds per square inch; again heating the cylinder by externally applied heat and admitting steam into the cylinder 125 from the bottom until a pressure of about 100 pounds per square inch is obtained whereby to speedily separate the rosin and

turpentine from the wood in the absence of air; allowing said steam to escape during the maintenance of said last-named pressure by the continued injection of steam until all of the turpentine is recovered; stopping the introduction of steam and allowing the pressure in the cylinder to subside; carrying off the turpentine product by the resid-

ual steam pressure; and then removing the wood pulp, substantially as described. 10

In testimony whereof, I affix my signature, in presence of two witnesses.
